UNITED STATES PATENT OFFICE

MARCEL LOBELLE, OF HAYES, ENGLAND, ASSIGNOR TO CHARLES RICHARD FAIREY, OF HAYES, ENGLAND

AEROPLANE RADIATOR

Application filed October 16, 1928, Serial No. 312,840, and in Great Britain October 27, 1927.

This invention relates to radiators particularly those for use on aircraft, whether of the heavier or lighter-than-air type, and although it can be adapted for use with radiators for other purposes, such as fast motor boats or cars for example, it will be described particularly with reference to aircraft.

It has been found desirable, that, when so-called surface radiators are employed on aircraft, the effective cooling area should be capable of being varied according to temperature conditions, whilst in some circumstances there is a risk that those parts of a radiator system which are not, for the time being, in circuit, may become frozen. The object of the present invention is to arrange the radiator tubes or the like and the controlling elements thereof, as to obviate this risk, and for this purpose a radiator comprises two or more series of tubes or the like arranged in regularly or irregularly interspersed sequence, and so connected with the water jacket of the engine (or with a like container) that one series of tubes is always in circuit whilst the other or others may be cut out at will, the interspersion of said tubes enabling the heat radiated or otherwise transmitted from the series of tubes in circuit to prevent the water or the like in those which are not in use from becoming cooled unduly or freezing.

In order to obtain the desired regulation of the effective area of the radiator the opposite ends of the tubes of the first series of tubes may be in open connection with the water jacket of the engine, one end of each tube of the second series, and of each subsequent series, if any, being in open connection with said water jacket, and the other end of each tube of the second series, and of each subsequent series, if any, being in valve-controlled connection with said water jacket, whilst, preferably, a valve-controlled bye-pass is adapted to establish direct connection between the pipes leading to and from said water jacket, the arrangement being such that the first series of tubes is always in circuit whilst the second series (and each subsequent series, if any) may be cut out of circuit, (successively), the bye-pass, if provided, being opened (progressively) as the second

series (and each subsequent series, if any) is so cut out of circuit.

It is desirable that when a bye-pass is provided the valves controlling the passages should be interconnected so as to be operable concurrently and progressively. In the accompanying drawings Figure 1 is a diagrammatic perspective view showing one manner of carrying out the invention; Figures 2, 3 and 4 are enlarged diagrammatic cross-sections of some of the radiator tubes showing the tubes of all the series in action, one series cut out and two series cut out, respectively. Figures 5, 6 and 7 are enlarged diagrammatic cross-sections of the controlling cocks under like conditions, respectively; Figure 8 is a diagrammatic perspective view of a part of a modified arrangement; Figure 9 is an enlarged diagrammatic perspective view of the combined controlling cock; and Figures 10 and 11 are cross-sections of the controlling cock shown in Figure 9.

Referring first to the form of the invention illustrated by Figures 1 to 7, a pipe *a* leading from the water jacket (not shown) of an aeroplane engine is connected with one end of each of the tubes of three series *b* . . . . , *c* . . . . , *d* . . . . , constituting a radiator, the opposite ends of which are connected by pipes *e*, *f*, *g* with the return pipe *h* to the water jacket, and those ends of the tubes *b* . . . . , *c* . . . . , *d* . . . . , which are connected with the pipe *a*, are connected also with the return pipe *h* by a bye-pass pipe *j*. The latter and the outlets *f* and *g* from the second and third series of tubes *c* . . . . , and *d* . . . . , are provided each with its controlling valve, *k*, *m*, *n*, e.g. a spigot valve, the valves *k*, *m*, *n* being interconnected mechanically by crank arms *o*, *p*, *q* and a rod *r* and the ports *s*, *t*, *u* (Figures 5, 6, and 7) of said valves being so proportioned and arranged relatively to one another that initial movement of the operating rod *r* and crank arms *o*, *p*, *q* from the normal position corresponding with the positions of the valves shown in Figure 5 when water passes through all the tubes *b* . . . . , *c* . . . . , *d* . . . . , as shown in Figure 2, will close the valve *n* of the series

of tubes $d \dots$, and open slightly the valve k of the bye-pass j as shown in Figure 6, when water will pass only through the series of tubes $b \dots$, and $c \dots$, as shown in Figure 3, whilst further movement will close the valve m of the series of tubes $c \dots$, (maintaining closed the valve n of the series $d \dots$), and open still further the bye-pass valve k as shown in Figure 7, when water will pass through the series of tubes $b \dots$, only, as shown in Figure 4, said series of tubes $b \dots$, being always in circuit.

Figures 8 to 11 show how the passages may be controlled by a single valve v , e. g. a sleeve valve, into the casing of which the outlet pipes e, f, g , from the three series of tubes $b \dots, c \dots, d \dots$, open in angularly spaced relationship in the same transverse plane, as shown in Figures 9 and 10, whilst the bye-pass pipe j opens thereinto in a different transverse plane, as shown in Figures 9 and 11, the sleeve valve v itself leading interiorly by the pipe h to the water jacket (not shown) of the engine and being provided with a port w adapted to control the outlet pipes f and g and with a tapered port x adapted gradually to vary the effective cross-sectional area of the bye-pass pipe aperture so that the latter is opened and increased progressively as the outlet pipes f and g are closed.

In this form of the invention the bye-pass pipe j is connected directly between the pipes a and h , the position of said bye-pass pipe and the valve v being indicated in broken lines in Figure 1.

The arrangement of tubes and the control of the circuit is independent of the formation of the tubes themselves, of the nature of the fluid flowing therethrough, and of the purpose to which the radiator is put, but if the radiator be constructed in accordance with the specification of Letters Patent No. 246,231, heat will be transferred to those tubes which, for the time being, are cut out of circuit, not only as a result of the interspersion of the tubes but also as a result of the direct contact of all the tubes with the corrugated back plate of the radiator.

The invention may be applied also to the tubes of an ordinary tube-block type of radiator.

I claim:—

1. A radiator of the class described, comprising a plurality of series of cooling tubes adapted to be connected with the inlet and outlet openings of the water jacket of an engine, the tubes of a first series of said cooling tubes being in interspersed sequence with the tubes of the subsequent series and permanently in open circuit, each of said subsequent series of tubes having a valve mounted therein, said valves being interconnected, means for operating said valves concurrently and pro-

gressively, a valve controlled by-pass between the inlet and outlet tubes of the cooling system, and means for opening said by-pass progressively as each subsequent series is cut out of circuit.

2. A radiator as in claim 1 in which the valves controlling each of the subsequent series of cooling tubes are combined in a single sleeve valve, the parts of the pipes connected with the series of cooling tubes being in angularly spaced relationship in one transverse plane.

3. A radiator as in claim 1 in which a single sleeve valve controls each of the subsequent series of cooling tubes, the parts of the pipes connected with the series of cooling tubes being in angularly spaced relationship in one transverse plane, the pipe of the by-pass being in a different transverse plane, said sleeve valve being formed with a tapered part adapted to gradually vary the effective cross sectional area of the by-pass aperture, whereby the latter is opened progressively as each of the subsequent series of tubes is closed.

4. A radiator for use on an aeroplane or for a similar purpose comprising a plurality of series of tubes or the like, the tubes of one series being arranged in interspersed sequence with those of another, said tubes being connected with the water jacket of the engine, one series of tubes being always in circuit, means for enabling the remainder to be cut out at will, a valve controlled by-pass arranged between the pipes leading to and from said water jacket whereby said by-pass may be opened progressively as each subsequent series is cut out of circuit.
